(57) **CLAIM**

The ornamental design for the light tunnel for electrosurgical pencil, as shown and described.

DESCRIPTION

FIG. 1 is a perspective view of the light tunnel for electrosurgical pencil.

FIG. 2 is a first side view of the light tunnel for electrosurgical pencil.

FIG. 3 is a second side view of the light tunnel for electrosurgical pencil.

FIG. 4 is a first end view of the light tunnel for electrosurgical pencil.

FIG. 5 is a second end view of the light tunnel for electrosurgical pencil.

FIG. 6 is a top view of the light tunnel for electrosurgical pencil.

FIG. 7 is a bottom view of the light tunnel for electrosurgical pencil; and,

FIG. 8 is a perspective view of the light tunnel for electrosurgical pencil as located for use.

The broken lines shown in the figures are included for the purpose of illustrating portions of the light tunnel for electrosurgical pencil and form no part of the claimed design.

The broken away symbols in the drawings indicate that any portion of the article beyond what is shown forms no part of the claimed design.
